Claims priority, application Republic of South Africa
Mar. 23, 1967

Term of patent 14 years

Int. Cl. D6—01; D19—02; D27—05

U.S. Cl. D48—27

The drawing is an isometric view of a base for a cigarette lighter or the like according to my design. The article has a regular geometrical shape as illustrated, with the bottom face being of the same shape and configuration as the top face and similarly unornamented, and with the side and rear faces following the same lines and arrangement as the front faces shown and being similarly unornamented.

I claim:

The ornamental design for a base for a cigarette lighter or the like, substantially as shown and described.
